W. D. McPHERSON.
AUTOMATIC AIR AND GAS VALVE FOR CARS.
APPLICATION FILED AUG. 4, 1908.

909,320.

Patented Jan. 12, 1909.

UNITED STATES PATENT OFFICE.

WARREN D. MCPHERSON, OF CHICAGO, ILLINOIS.

AUTOMATIC AIR AND GAS VALVE FOR CARS.

No. 909,320.

Specification of Letters Patent.

Patented Jan. 12, 1909.

Application filed August 4, 1908. Serial No. 446,953.

To all whom it may concern:

Be it known that I, WARREN D. MCPHERSON, a citizen of the United States, residing at Chicago, in the county of Cook and State 5 of Illinois, have invented certain new and useful Improvements in Automatic Air and Gas Valves for Cars, of which the following is a specification.

The invention relates to automatic valve 10 means for shutting off the gas supply to the lights on a car, and automatically applying the air brakes of said car, simultaneously with the shutting off of the gas.

In many instances the principal damage 15 caused by a train of cars or a car leaving the track, is due to the fact that it cannot be stopped sufficiently quick to prevent the same from going over an embankment, and secondly, that if said car or train of cars does 20 go over an embankment, a fire results, due to the fact that the gas is turned on when the car is upside down or in whatever position it may be.

The object of my invention is therefore, 25 first, to stop a car or train of cars almost instantly, by applying the air brakes, if the same leaves the track or in case of a collision or a severe contact with another object. And a second object of my invention is to 30 automatically shut off the gas, simultaneously with the application of the air brakes, in case of any of the events taking place, as above mentioned. To accomplish these objects, each car is provided with a weight or 35 pendulum, operating two valves if an unusual or severe shock is imparted to the car longitudinally; the invention consisting in the combination of the weight or pendulum with the valves, which will be more specifically described and shown in the accompany- 40 ing drawing, in which—

Figure 1 is a top plan view of my invention, and Fig. 2 is a vertical section of Fig. 1; Fig. 3 is a detailed view of the pendulum and 45 trip for the valve stems. Fig. 4 is the section on the line 4—4 of Fig. 2, and Fig. 5 is a section on the line 5—5 of Fig. 2; Fig. 6 is a detailed view of the device for regulating the escapement of the air for the air valves.

50 Referring now more particularly to the drawings, 7 represents the floor of a car to which a plate 8 is secured by means of the screws 9.

10 and 11 are gas and air valve casings, 55 respectively, secured to the plate 8 by means

of the screws 12. The gas valve casing 10 being provided with the valve 13 having the central opening 14 communicating with the gas pipe 15 to allow the gas to pass through said pipe. The valve 13 is provided with an 60 upwardly extending portion 16, opening into a countersunk portion 17, in the floor of the car, whereby a wrench or the like can engage the square head 18 of the upwardly extending portion, to open said valve. A shoulder 65 19 is formed at the top of said valve to limit its rotating movement. The bottom portion of the valve 13 is cut away at 20 to form a seat for the spring 21, which encircles the valve stem 22; the spring engaging the valve 70 stem at 23 at one end and secured to the casing, whereby the tension upon the valve is to normally hold the same in a closed position.

Referring now to the air valve 24, the 75 same is provided with an opening 25, adapted to register with the opening in the air pipe 26, said air valve 24 being cut away, so as to provide a cushion chamber 27 within the casing, before the air passes therefrom. The air 80 valve casing is provided, preferably at its top, with an escapement passage 28, which extends through the casing into the plate 8 in a vertical manner, and a lateral communicating passage 29 communicates with the 85 vertical passage 28, said communicating passage 29 having a threaded escapement valve 30 secured thereto, with an escapement port 31 therein and a thumb screw 32, provided with beveled end 33 adapted to close the port 90 31, or open the same, for the purpose of adjusting the escapement of air from the chamber 27. The lower portion of said air valve 24 is cut away at the bottom and provided with a spring the same as the cut away portion 20 and spring 21 heretofore referred to, 95 also tending to close said valve. The valve 24 is provided with stem 34, both the stems 22 and stems 34 passing through an annular opening 35 in the bottom of said valves and caps 36 having a threaded engagement with annular bosses 37 on the valve casings, for the purpose of packing the valve.

To each valve stem, arms 39 are secured, 100 which project laterally therefrom and have 105 seats 40 at their outer ends. The valve casings are provided with adjacent bosses 41, through which trip stems 42 pass, the bosses 41 being provided with spring seats 43, having springs 44 therein, surrounding said trip 110

stems; said springs abutting against the top of said seats and having bearings upon annular shoulders 45 formed on said trip stems; the object of said spring being to always hold the heads 46 on said trip stems in the seats 40 in the arms 39. Caps 47 have a threaded engagement with said bosses 41 to close the ends of said spring seats.

To the top of each trip stem are secured 10 trip arms 48, having downwardly projecting lugs 49. The adjacent bosses 41 on said valves are sufficiently apart to form a vertical passage between the same, in which is pivoted a pendulum 50 by means of the pivot pin 51, passing through said pendulum and through depending parts on said bosses. The pivot pin 51 also passes through a double cam member 52, secured to the pendulum. Said pendulum also carries a weight 53, held 15 thereon by means of the nut 54, having a threaded engagement with the lower portion of said pendulum. The cam member 52 is so constructed that the depending lugs 49 and the trip arms 48 extend between the two 20 cam surfaces 55 and 56 on said cam, whereby rocking of the cam in either direction will operate said trip arms 48.

In Fig. 1, 57 and 58 represent the air and gas pipe couplings, respectively. It can be 30 seen that the gas valve may be re-set from the interior of the car, but for the purpose of re-setting the air valve, a lever 59 is secured to the stem 34, which extends through arms 39, and rods 60 are attached to each end of 35 said lever arm and extend to either side of the car body for the purpose of re-setting the valve, exteriorly of the car after the same has been opened.

Figs. 1 and 2 in the drawings show the 40 device as the same would be applied to a car, *i. e.*, the gas and air pipes run longitudinally of the car, while the valves are set in alignment transversely of the car, so as to bring the pendulum in a position whereby it will 45 swing longitudinally of the car only.

It can be readily seen, therefore, from the foregoing description, that if there is a collision or the car leaves the track, or if the car body receives any other severe jolt or 50 bump outside of the ordinary kind, that the weight at the bottom of the pendulum would be carried forward by the momentum, provided the car was traveling in a forward direction, which movement of the pendulum 55 would rock the cam 52, causing the cam surface to come in contact with the trip arms 48 and lifting the same, which would draw the trip stems 42 from the arms 39, and release the springs 21 in the air and gas 60 valves; the result tending in the first instance to apply the air brakes, and in the second instance to close the gas valve, thereby instantly and automatically applying the air brakes and cutting off the supply of gas.

65 The weight 53 and the pendulum is so

proportioned that any usual or ordinary jars would not affect the same in any way, and by means of the threaded engagement of the nut 54 with the pendulum 50, the weight 53 may be either raised or lowered to 70 regulate the swinging of the pendulum so that the same will be affected more easily by either a light or a severe contact.

It is to be understood that the weight or pendulum does not come in contact with any object whatsoever, the same being operated only by the momentum of the car and the force of the contact. It is further of course obvious that by means of the two cam faces upon the cam 52 that the pendulum will 80 operate irrespective of whether the car is traveling forward or backward, and consequently no attention need be paid as to the manner in which the cars are coupled together.

It is apparent that various changes might be made in the construction herein shown, and therefore, without limiting myself to the details of construction,—

I claim:

1. An automatic air and gas valve mechanism for a car, consisting of two valves for air and gas connected to the main pipes, respectively, a weight arranged to swing relative to the car body, and means connected with said valves whereby the movement of said weight will operate to close said valves, substantially as described.

2. An automatic air and gas valve mechanism for cars, consisting of two valves for air and gas connected to the main pipes respectively, a weight arranged to swing longitudinally relative to the car body, and means connected with said valves whereby the movement of said weight will operate to close the same, substantially as described.

3. In an automatic air and gas valve mechanism for cars, the combination with the train pipes of an air brake system and a gas pipe system, of a pair of valves connected to said pipes for air and gas respectively, springs secured to each valve for normally holding the same in an open position, a weight arranged to swing longitudinally relative to the car body, and means between said springs and weight whereby the movement of said weight will operate to close said valves, substantially as described.

4. An automatic air and gas valve mechanism for cars, consisting in the combination of a train pipe of an air brake system and a train pipe of a gas system, of an air and gas valve secured to said respective train pipes, arms connected to said valves, trip stems engaging said arms, a weight arranged between said trip stems, springs normally tending to close said valves, and means on said weight for releasing said arms, whereby said springs will close said valves, substantially as and for the purposes described.

5. An automatic air and gas valve mechanism for cars, consisting of a pair of valves in line with the air pipe and gas pipe of a train, a weight arranged between said valves, 5 an arm secured to the stem of each valve, springs for normally closing said valves, and means for holding said valves open, consisting of a trip stem adapted to engage said arms to prevent their movement, and means 10 for closing said valves, consisting of a cam member secured to said weight and adapted to release said trip stems upon a movement of said weight.
6. An automatic air and gas valve mechanism for cars, consisting of a valve in the 15 train pipe of the air brake system and a valve in the train pipe of the gas system, a pendulum arranged between said valves, provided with a weight at one end and a cam at its 20 other end, springs engaging said valves, normally tending to close the same, and means for holding said valves in an open position, consisting of arms secured to the valves, trip stems engaging said arms, to hold the valves 25 open against the action of said springs, a trip block secured to said trip stem in the path of the cam, whereby a rocking of the pendulum will release said arms, for the purpose of closing said valves, substantially as 30 described.
7. The combination with the train pipe of an air brake system and a train pipe of the gas system, of a pair of valves secured to a car in an open position, to allow the air and 35 gas respectively to pass therethrough, springs normally tending to close said valves, means for holding said valves in an open position, consisting of arms secured to said valves, trip stems adapted to engage said arms and 40 to hold the same against the action of said springs, and means for closing said valves, consisting of a pendulum pivoted between the same, a weight at one end of said pendulum, a cam at the other end thereof, adapted 45 to engage the ends of said trip stems upon a rocking movement of said pendulum, for the purpose of releasing the arms and allowing
8. An automatic cut-off for railway cars and other vehicles, comprising a valve located in the gas pipe line at a suitable point between the gas reservoir and the burners, a pendulous weight, a spring normally tending to close said valve, means for holding said valve in an open position against the action of said spring, and means between said pendulous weight and valve for releasing the means holding said valve in an open position, whereby the action of said spring will close 50 said valve upon a swinging movement of said weight longitudinally relative to the car body, substantially as described.
9. An automatic cut-off for railway cars and other vehicles, comprising a valve located in the air pipe line, a pendulous weight, a spring normally tending to close said valve, means for holding said valve in an open position against the action of said spring, and means between said pendulous weight and 55 valve for releasing the means holding said valve in an open position, whereby the action of said spring will close said valve upon a swinging movement of said weight longitudinally relative to the car body, substantially as described.
10. An automatic cut-off for railway cars and other vehicles, comprising a valve located in the gas pipe line at a suitable point between the gas burners and reservoir, a 60 valve located in the air pipe line, a pendulous weight located between said valves, spring means secured to said valves tending to close the same, means for holding said valves in an open position against the action of said 65 spring means, cam means carried by said pendulous weight for releasing said springs thereby closing said valves, and means for re-setting said valves, substantially as described.
